UNDERGARMENT

Arthur R. Kneibler, Kenosha, Wis., assignor to
Cooper's, Incorporated, Kenosha, Wis., a cor-
poration of Wisconsin

Application June 22, 1938, Serial No. 215,093

1 Claim. (Cl. 128—159)

This invention relates to undergarments and more particularly to undergarments of the shorts type for men's wear.

The main objects of the invention are to provide an undergarment of the character indicated in which the crotch portion of the garment is so constructed as to afford a highly desirable, mild supporting effect; to provide a construction which will avoid excessive stretching of the garment when made of knitted material so as to be capable of indefinitely retaining its initial, built-in, form fitting and supporting qualities; to provide in an undergarment of the character indicated a waist band structure which will supply a comfortable abdominal supporting effect; and, in general it is the object of the invention to provide an improved garment of the character indicated.

Other objects and advantages of the invention will be understood by reference to the following specification and accompanying drawings (3 sheets) wherein there is described an undergarment of the men's shorts type embodying a selected form of the invention.

In the drawings:

Figure 1 is a front elevation.

Figure 2 is a rear elevation.

Figures 3, 4 and 5 are sections on the correspondingly numbered lines in Figure 1.

Figure 6 is a section on the line 6—6 of Figure 5.

Figure 7 is a fragmentary plan of the lower crotch portion of the garment.

Figure 8 is an exploded view showing the various parts which enter into the construction of the improved garment.

Referring now to the drawings, the garment as therein shown comprises a waist band portion 10 and a body portion 11.

The waist band portion 10 is preferably formed of front and back sections 12 and 13, respectively, the said sections being joined together at the sides of the garment as indicated at 14—14.

The front section 12 is formed of elastic webbing, i. e., knitted material containing elastic threads of rubber or like material which extend in the direction of the circumference of the waist band so that said front section is circumferentially stretchable. The material is preferably such that it has no appreciable stretchability in the vertical direction of the garment. The front section 12 is preferably widened somewhat in its middle portion so as to overlie most of the lower abdominal regions of the wearer and thereby to exert a desirable supporting effect on the same.

The rear section 13 is preferably formed of relatively inelastic material and in this instance comprises three plies, 13a, 13b, and 13c, of woven fabric of suitable weight and in addition a pair 5 of tape-like fabric strips 13d—13d. The tape-like strips are arranged to extend transversely of each other and diagonally of the back section 13, as best shown in dotted lines in Figure 2. The said strips are preferably located between 10 the two innermost plies of the back section but without attachment to the innermost ply, and said two plies and strips are stitched along the edges of the tape strips intermediate their outermost ply so the stitching presents a quilted effect on the outside of the back section. The innermost ply of the back section covers the diagonal lines of stitching and the assembled back structure is stitched together about the periphery thereof either by stitching provided for that purpose only, or as an incident to stitching which is employed for uniting the back section to other parts of the garment.

The front waist band section is suitably knitted so as to present a finished upper edge and 25 it is also preferably formed with an upper marginal portion which embodies a greater number of elastic threads than the remainder of the section, so as to supply stronger elasticity in the upper margin to thereby insure adequate gripping of the body to keep the garment in place. The upper edge of the back section is preferably 30 trimmed with a tape-like strip 15 of knitted material, the latter being preferably formed by folding a strip of the knitted material upon itself to 35 form a two-ply element with one edge formed by the fold. The finished edge so formed provides a relatively soft and comfortable gripping margin for the back section of the waist band. As indicated in Figures 2 and 8, the upper edge of the back section is slightly concaved, this shape serving to better conform the upper portion of the garment to the body.

The described waist band construction places 40 substantially all of the elasticity therein in the front portion where it overlies the portions of the body which undergo the greatest movement, whereas the back section is so constructed it may 45 assume a substantially fixed position in the back of the wearer where little or no movement takes place. This arrangement produces a desirable 50 comfort effect as distinguishable from conventional arrangements in which the waist band embodies elastic material around its entire circumference.

55 The body section of the garment comprises leg-

forming portions 16 and 17, the same being shown in Figure 8 in a folded condition to more adequately illustrate their relationship to the other parts of the garment. The leg sections 16 and 17 have their upper end portions 18-18 respectively joined to adjacent end portions of the elastic and inelastic front and back sections 12 and 13 of the waist band. Lower inside edge portions indicated at 19 of the said leg sections are joined together by suitable seams as indicated at 20 (in Figure 1) and the lower ends of said leg sections are turned outwardly and inwardly and secured by suitable stitching as indicated at 21 to form the legs of the desired length.

On the back of the garment intermediate the two leg sections there is a back element 22, the same having its upper edge 23 secured to the waist band and its side edges 24-24 secured by suitable stitching as indicated at 25 to the adjacent upper side edge portions of the leg sections 16 and 17.

A crotch portion 26, preferably formed of two plies of material as indicated in Figure 8, has its rear edge 27 united by suitable stitching 28 to the lower edge of the back section 22. The side edges 29-29 of the crotch portion 26 are united by continuations of the stitching 25 to the central and lower front portions of the upper side edge portions of the leg sections 16 and 17 as is apparent from an inspection of Figures 1 and 2 of the drawings. As best shown in Figure 1, the said crotch portion 26 extends upwardly to a point where it overlies a lower central portion of the waist band, said upper end portion being pointed substantially as indicated in the drawings.

The front of the garment is completed by means of inserts 30 and 31, respectively, on opposite sides of the pointed end of the crotch portion, the insert 30 being of triangular form and having its edges joined by stitching to the adjacent edge portions of the waist band and the leg 17. The third edge of the insert 30 underlies the adjacent edge portion of the pointed end of the crotch member 26 and is suitably secured thereto a tape-like strip 32 of suitable fabric being stitched adjacent its edges as indicated at 33-33 to the underlying margins of the garment portions 26 and 30. Said tape-like strip 32 may be formed of a knitted material with the wales extending lengthwise of the strip so that the latter is relatively inextensible lengthwise and said strip preferably extends transversely of the front section of the waist band to the upper edge thereof so that said strip is effective to transmit support from the waist band to the front end of the crotch portion and through the seam 25 and adjacent portions of the garment to the lower or central portion of the crotch of the garment.

The other triangular insert element 31 also has edge portions united to the adjacent edges of the waist band and leg portions, but its third edge 34 is left free except at its ends to the overlying portions of the garment. The said edge 34 is preferably finished with a suitable tape-like strip and it is generally parallel to the edge 35 of the pointed end of the crotch portion. The said edge 35 of the crotch portion is also free except for attachment at its ends to the underlying portions of the garment. As shown, the upper end of the free edge portion 35 is secured by stitching to the central portion of the garment in the waist band thereof and the lower end of said edge is secured preferably as an incident to the stitching 25. It will be seen that the material of the front

end of the crotch portion 26 and of the insert 31 overlaps a substantial distance but is free of inter-attachment, thereby forming a front opening in the garment.

The structure thus far described obtains the advantageous supporting effect more fully set forth in my Patent No. 2,019,140, A. R. Kneibler.

By preference the body portion of the described garment is made in its entirety of knitted material, the wales of which extend generally in the direction of the length of the garment. Such knitted material is more or less elastic transversely of its wales so that the garment may be distended as may be required to fit the wearer with a desirable degree of snugness.

For the purpose of controlling the transverse stretching of the garment especially in the crotch portion there is provided in this instance a short tape strip 36 preferably of woven fabric material

which is relatively inelastic. Said tape strip 36 is located substantially in the lowermost portion or middle of the crotch of the garment and it is secured at its ends to the opposite edges 29-29 of the crotch portion, preferably by means of the stitching 25. As indicated in Figure 8, the crotch tape element 36 is of considerable less length than the corresponding width of the crotch portion 26. The crotch portion is preferably gathered together as indicated at 36 (in Figure 6) adjacent the tape strip and securely attached throughout the width of its gathered portion to the tape strip by means of suitable machine stitching as indicated at 38. Said stitching 38 maintains the crotch portion gathered as explained and said gathers extend forwardly and rearwardly from the tape strip 36 so as to produce somewhat of a pouch effect, both forwardly and rearwardly of the said tape strip. Such pouch effect, however, is more pronounced at the front of the crotch tape due to the greater width of material in the adjacent portions of the crotch forwardly of the strip. It will be evident that the gathers 37 have a normal tendency to stay closed incident to the stitching 38 but that they may readily be distended as the need requires to conform to and support the body with a mild, resilient, supporting effect.

The structure described requires no special or difficult manufacturing operations and may be produced economically and at low costs so as to be a commercially practicable construction. It embodies definite advantages of body support and lasting qualities in respect of said supporting effect, and in this latter respect overcomes disadvantages present in constructions now available and which aim to provide a comparable supporting effect.

Changes in the described structure may be made without departing from the spirit of the invention, the scope of which should be determined by reference to the following claim, the same being construed as broadly as possible consistent with the state of the art.

I claim:

A man's undergarment made of knitted material having substantially vertically extending, relatively non-extensible wales and which is stretchable circumferentially and adapted to fit snugly all parts of the body so that the material of the garment is under tension circumferentially while being worn, said garment having a waist band which exerts a constrictive force and serves to at least partially support the garment from the waists of the wearer; a front panel attached to said waist band and tapering downwardly to

ward the crotch and having such width at the crotch as to provide a masculine support; a rear panel extending upwardly and rearwardly from said crotch portion and connected at its upper edge to said waist band; side panels forming lateral coverings for the trunk and thighs between said front and back panels and connected thereto along their adjacent edges to form a complete garment, the lower portions of said side panels forming integral tubular legs extending downwardly from said crotch; the seams connecting the upper edges of said side panels to said front panels being disposed along lines substantially coincident with the groins of the wear-

er and being capable of exerting a pulling force sufficient to resolve and transmit the lateral and vertical forces of the front and leg panels in the upper part of the garment; said crotch portion being stretchable transversely and being gathered across its width at the base thereof; and an inextensible member extending transversely of said crotch portion at the location of said gathers and of a length less than the width of the adjacent crotch portion, whereby said gathers are maintained in said garment and said inextensible member resists transverse stretchability of said crotch at the base thereof.

ARTHUR R. KNEIBLER.
